United States Patent

Des. 239,997
Patented May 25, 1976

239,997

PHOTO FRAME

Ralph R. Burin, Glen Ellyn, and Harold Stelicha, Wilmette, Ill., assignors to Intercraft Industries Corporation

Filed Sept. 9, 1974, Ser. No. 504,554

Term of patent 14 years

Int. Cl. D6—07

U.S. Cl. D6—236

FIG. 1

FIG. 2

FIG. 3

FIG. 4

FIG. 1 is a front elevational view of a photo frame showing our new design;

FIG. 2 is a top plan view of the frame of FIG. 1 with the easel support in the storage position;

FIG. 3 is a rear elevational view of the frame of FIG. 1; and

FIG. 4 is a side elevational view of the photo frame of FIG. 1, with the easel support in its use condition.

We claim:

The ornamental design for a photo frame, substantially as shown.
